(57) **CLAIM**

The ornamental design for a seed sprouter tray, as shown and described.

DESCRIPTION

FIG. 1 is a perspective view of a seed sprouter tray showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a perspective view of the seed sprouter tray shown in an alternative configuration with the top cover flipped;

FIG. 10 is an exploded perspective view of the seed sprouter tray; and,

FIG. 11 is a top perspective exploded view of the seed sprouter tray.

The broken lines illustrate portions of the seed sprouter tray that form no part of the claimed design.

1 Claim, 11 Drawing Sheets
